UNITED STATES PATENT OFFICE.

MAUDE ARMSTRONG, OF DENVER, COLORADO.

TELEPHONE STAND.

Application filed August 13, 1923. Serial No. 657,104.

To all whom it may concern:

Be it known that I, MAUDE ARMSTRONG, a citizen of the United States, residing at Denver, in the county of Denver and State of Colorado, have invented certain new and useful Improvements in Telephone Stands, of which the following is a specification.

My said invention relates to a telephone stand and it is an object of the same to provide means for holding the receiver in convenient position thereby obviating the necessity of laying down the work in hand and lifting the receiver and also doing away with the necessity of holding the receiver while waiting for connections, etc.; also to provide a convenient means for making and breaking connection; also to provide in connection with the stand an amplifier which will enable the user to hear without holding the receiver close to his ear; also to keep out outside noises when using in noisy places, and to enable those slightly deaf to hear over the telephone by keeping out such noises and amplifying the sounds coming over the telephone.

Referring to the accompanying drawings, which are made a part hereof and on which similar reference characters indicate similar parts,

30 Figure 1 is a front elevation of my device,

Figure 2, a plan,

Figure 3, a detail of a blank entering into the construction of the amplifier,

35 Figure 4, a sectional detail of the outer or forward edge of the amplifier,

Figure 5, a view partly in section illustrating the means for holding the receiver on the stand,

40 Figure 6, a detail of a blank of part of the means for making and breaking connection, and

Figure 7, a plan of such means in its completed form.

45 In the drawings reference character 10 indicates a telephone of ordinary form having a mouth piece 11 and a hook 12 by means of which the receiver 13 is ordinarily supported when the telephone is not in use, this hook serving also to make and break the connection, as usual.

A sleeve 14 surrounds the upright post of the telephone and has projecting to one side a finger 15 adapted for engagement by the thumb and finger of the operator. The sleeve has a cam slot 16 (Fig. 6) engaging

the shank of the hook 12 and is provided at its ends with holes 17 to receive one or more bolts 18 for holding the sleeve in place. A lining 19 of felt is interposed between the post and sleeve to prevent friction between the parts. The sleeve is shown in open position i. e. in the position assumed when the telephone is in use, in Figure 1, and carries at its front side an inscription which as here shown may read "Don't leave open." As will be evident when the telephone is to be used the thumb will be pressed against the finger 15 to turn the sleeve in counter-clockwise direction about the post whereupon the hook rises and the inscription comes into view. When the conversation terminates the index finger of the user will be in convenient position to engage the other side of finger 15 and turn the sleeve to lower the hook and move the inscription out of sight or approximately so.

A sheet metal bracket 20 has a rearward extension in the form of an ear 21 secured to the upper end of the telephone by a screw 22 forming part of the usual pivot for the mouth piece. The ear connecting the bracket 20 and the post may be integral with the bracket but preferably is hinged as indicated at 24 so that the receiver may be swung back out of the way of the user or into convenient position for another person to use it without moving the stand. This bracket also has an extension 23 bent at an angle of 45 degrees and adapted to support the receiver at its extreme end. It will be noted that the bracket 20 is extended to the right to partially counterbalance the weight of the receiver and connected parts and the extension at this side may be weighted to accentuate this action.

A blank 25 (Fig. 3) provides an amplifier for the receiver as well as means for holding it in place on the stand. For this purpose the blank is bent to bring the holes 26 into registering relation and rivets or other holding means are provided to secure the parts in position to surround and engage closely with the ear piece 27 of the receiver. The forward end of the amplifier of this form is provided with a rim 28 of rubber or fabric such as felt. It will be noted that the rim is so shaped as to fit snugly about the ear and against the head so that the user may position it in a manner to exclude external sounds although it is intended to be large enough to magnify the sound of the tele-

phone sufficiently so that it will not be necessary to keep the head close to the receiver in the course of a conversation.

The blank 25 has an arm 29 adapted to extend parallel to the body of the receiver and at its rear end has a pair of fingers 30 arranged to be clamped about the shank of the receiver close to its neck and connected by rivets 31 or the like. The arm of the blank 10 is provided with a slot 32 located underneath the receiver and arranged to register with a hollow in the arm 23. A bolt 33 passes through the hole and the slot and is provided with a thumb nut 34 by means 15 of which the parts can be held securely together, adjustability being provided by means of the slot so that the receiver can be moved further from or closer to the mouth piece in an obvious manner.

20 As will be evident to those skilled in the art my device may be modified in various ways without departing from the spirit of the invention and therefore I do not limit myself to the specific device shown in the 25 drawings and described in the specification but only as indicated in the appended claims.

Having thus fully described my said invention, what I claim as new and desire to secure by Letters Patent, is:

30 1. A telephone stand comprising an amplifier surrounding the ear piece of the telephone receiver having an arm extending rearwardly therefrom and secured to the rear end of the receiver, a hinged bracket 35 pivoted on the post of the telephone, means for connecting said bracket to said arm with the receiver in front of the telephone mouth-piece and spaced from one side thereof, and means for adjusting the arm relatively to 40 the bracket to vary such spacing, substantially as set forth.

2. In a telephone stand, a device comprising a sheet metal blank having arms adapted to be bent about the ear piece of the receiver 45 to form an amplifier, a slotted arm extending rearwardly therefrom, fingers at the rear end of the arm adapted to be bent about the shaft of the receiver to secure the amplifier in place, and a bracket adapted to be connected to said arm and to the post of a telephone for supporting the receiver, substantially as set forth.

3. In a telephone stand, an amplifier sur-

rounding the ear piece of the receiver and having a cupped elliptical forward edge to 55 match the contour of the head, a protecting rim about the forward edge of the amplifier, and a hinged bracket pivoted to the post of the telephone and adjustably connected to said amplifier for holding the receiver in 60 place, substantially as set forth.

4. A device of the class described comprising a bracket, an element pivotally supporting said bracket to swing in a substantially horizontal plane, and a second element adjustably and pivotally supported by said bracket, said bracket having a counterbalancing portion extending on the opposite side of its supporting element, substantially as set forth.

5. A device of the class described comprising a pivotably mounted supporting element, a bracket pivotally carried by said element to swing in a substantially horizontal plane, and a second element adjustably and pivotally supported by said bracket, said bracket having one end extended beyond its supporting pivot to form a counterweight, substantially as set forth.

6. A device for supporting the receiver of a telephone in operative position comprising an ear supported on a horizontal pivot on the telephone post, a bracket pivoted on said ear to swing in a substantially horizontal plane, said bracket comprising a body member having one end portion extending at an angle of substantially 45° and bent upwardly for supporting the receiver of the telephone, and means for adjustably supporting a receiver on said end portion, substantially as set forth.

7. A support for a telephone receiver comprising a bracket having an element pivotally secured to the post of the telephone, a second element pivotally supported by said first mentioned element to swing in a substantially horizontal plane, said last mentioned element having an angular forwardly extending portion with means for supporting a receiver carried thereby, substantially as forth.

In witness whereof, I have hereunto set my hand and seal at Denver, Colorado this 7th day of August, A. D. nineteen hundred and twenty-three.

MAUDE ARMSTRONG. [L. s.]
